ADJUSTABLE SUPPORT FOR HAMMER DRILLS

Joy L. Glenn, Memphis, Tenn.

Application April 15, 1948, Serial No. 21,245

3 Claims. (Cl. 255—51)

1

This invention relates to adjustable supports for holding hammer drills against a structure into which a hole is to be drilled, and for applying pressure to the drill during the operation. Primarily it is especially adapted to drilling holes in ceilings which are more or less remote from the reach of the operator and fortuitously have a floor surface which provides a cooperative abutment against which the forces applied during drilling react.

In ordinary drilling, by use of rotary drills or other boring tools, it is known to use drills which are forced against the work by feed screws or levers which are manually operated to apply the proper pressure thereto. It is also known to provide adjustable supports through which adjustment to compensate for the distance between an abutment and the surface to be drilled may be provided. Securement after adjustment in such instances is usually provided by clamps, or more securely by holes and pins which effect more rigid attachment than do the clamps. These adjustments, however, while amply satisfactory for ordinary drilling, fail under the reaction stresses of hammer drills which cause slipping of the clamps, or distortion under the hammer blows of the more rigid adjusting means which rapidly makes them inoperative where change of adjustment is necessary.

An additional problem is met with in that in hammer drills vibratory shocks must be absorbed either by the structure or the person of the operator, and these conditions are accentuated where overhead drilling is done and the reaction of the weight of the body structure of the drill is not available to absorb the larger portion of the reaction shocks. Additionally, overhead drilling makes it advisable to apply the drilling pressure by foot power, leaving the hands free to steady and direct the more or less attenuated structure of the device.

The objects of the present device are:

To provide a simple, efficient and inexpensive support for a hammer drill, which support may be readily adjusted to compensate for distance between an abutment and the structure to be drilled into;

To provide a hammer drill support through which drilling pressure may be applied by foot power;

To provide a support for a hammer drill in which the pressure applying structure is connected through a resilient connector to the pressure originating member.

The means by which the foregoing and other objects are accomplished, and the manner of their accomplishment will readily be understood from the following specification on reference to the accompanying drawing, in which:

Fig. 1 is an elevational view of the support with

5 a hammer drill supported thereby in use position.

Fig. 2 is an enlarged sectional elevational view taken along the longitudinal axis of the device with the drill supporting head at 90 degrees to the head shown in Fig. 1.

Fig. 3 is a plan view of the device.

Fig. 4 is a sectional plan view taken on the line IV—IV of Fig. 2.

10 Fig. 5 is a fragmentary detail showing the preferred form of attachment of the foot pedal to the pressure applying cable.

Referring now to the drawings in which the various parts are indicated by numerals: 12 is a base to which a hollow post 14, preferably a length of pipe, is secured as by welding. Slidably disposed in the hollow post 14 is an extension member 16 which preferably also is a pipe, and mounted on the upper end of this member is a head 18 which preferably comprises a plate 18A secured to the member 16 as by welding, an overlying block 18B of the same length and breadth as the plate, and side blocks 18C cooperating to form a channel, the blocks 18B and 18C being secured to the plate 18A as by bolts 18D, and preferably being of wood for the absorption of drill shock. Preferably the side blocks are spaced to closely embrace the sides of the handle of the drill 19 which is to be used therewith, and if desired, the channel formed by the blocks 18B and 18C may be lined with an additional shock absorbing liner 18E as of linoleum, the entire channel structure being designably of destroyable nature and intended to be replaced from time to time as disintegration occurs and necessity requires. The drill used with the device forms no part of the present invention and no detail thereof is shown.

15 The extension member 16 is provided along one side intermediate its length with a series of holes 16A which are adapted for engagement by a hook 20. One side of the post 14 is provided with a longitudinal slot 14A through which the hook may be inserted and engaged with a selected 20 one of the holes 16A and along which it may freely slide. Adjacent the upper end of the post 14 are ears 22 which are rigidly secured to the post as by welding and which extend laterally outward from the post on either side of the slot 25 14A. The ears support a pin 24 which journals a grooved roller 26 over which is disposed a cable 28 which has one end fastened to the hook 20, extends therefrom over the top of the roller 26 and thence extends downward to a foot lever 30 35 immediately adjacent the base 12 and is secured to the lever adjacent one side of the post 14. The cable may have inherent resilience, or as shown in Fig. 5, attachment of the cable to the lever be made through a tension spring 32. Adjacent its bottom end the post 14 is provided

with diametrically opposite slots 14B of width to receive and loosely embrace the sides of the lever 30. The lever 30 is pivotally supported at one end by a pin 34 which is carried by ears 36 secured to and extending upward from the base 12. From the pin the lever extends through the slots 14B of the post, past the connection of the cable 28 to the lever and is provided with a foot pedal 38, a portion of which may be corrugated if so desired.

In using the device the drill 19 is placed in the channel of the head 18, and may be secured thereto if so desired, though no such securing means is shown, dependence preferably being had on the wedging of the drill handle between the side 18C of the head.

The base 12 of the drill is seated on the floor 40 or other suitable abutment directly below the location of the hole to be drilled and the extension member 16 raised by hand until the drill bit 42 engages the surface 44 to be drilled.

The hook 20 is engaged with the hole 16A accessible through the slot 14A adjacent the lower end of the slot 14A and the device is ready for use. The drill post 14 is steadied by hand and foot pressure is applied on the pedal 38 to hold the drill bit against the work and drilling proceeded with until the hole is completed, pressure is then released, withdrawing the bit, and shift made to other location.

It will be especially noted that the foot pressure applied to the pedal 38 is transmitted to the drill bit through the connecting cable 28, and that the resilience of this cable absorbs a considerable portion of the drill reaction. In many instances, however, the amount of vibration absorbed by the cable is insufficient and it is necessary to insert the spring 32 or equivalent shock absorber, but whether cable resilience alone or cable and spring resilience is relied on, the structure definitely includes a resilient connector between the pressure applying pedal and the bit.

It will be further noted that irrespective of the amount of extension of the support there is a minimum of change in the position of the foot pedal at the beginning of the operation.

It will further be understood that should a single depression of the foot pedal be insufficient to complete drilling of the hole to sufficient depth, that after the pedal has been pushed down to the limit, the extension member 16 may again be held by hand, the hook 20 be disengaged and reengaged with a lower hole 16A in the extension member and drilling be resumed.

I claim:

1. A support, as for a hammer drill, which support includes a base, a hollow post rigidly secured to and extending upward from said base, an extension member slidably disposed in said post and extending therefrom, said member terminating in a drill receiving head, and intermediate its length being provided with a plurality of holes adapted to engage a hook; said post being slotted in adjacency to said base, a foot pedal disposed through said slot and having one of its ends hingedly secured to said base, and its opposite end portion provided with a pedal plate, a pulley at the upper end of said post and members carried by said post journing said pulley, a resilient cable secured to said foot pedal extending to and over said pulley

and terminating in a hook adapted for engagement at option in any one of said holes, said post being slotted below said pulley to permit said hook engagement and hook shift under pedal action.

2. A support, as for a hammer drill, which support includes a base, a hollow post rigidly secured to and extending upward from said base, an extension member slidably disposed in said post and extending therefrom, said member terminating in a drill receiving head, and intermediate its length being provided with a plurality of holes adapted to engage a hook; said post being slotted in adjacency to said base, a foot pedal disposed through said slot and having one of its ends hingedly secured to said base, and its opposite end portion provided with a pedal plate, a pulley at the upper end of said post and members carried by said post journing said pulley, a tension spring secured to said foot pedal, a cable secured to said spring, extending to and over said pulley and terminating in a hook adapted for engagement at option in any one of said holes, said post being slotted below said pulley in alignment with said holes to permit said hook engagement and hook shift under pedal action.

3. A support, as for a hammer drill, which support includes a base, a hollow post rigidly secured to and extending upward from said base, an extension member slidably disposed in said post and extending therefrom, said member terminating in a head which includes a channel of resilient material conformed to receive and embrace slide portions of said drill, said extension intermediate its length being provided with a plurality of holes adapted to engage a hook; said post being slotted in adjacency to said base, a foot pedal disposed through said slot and having one of its ends hingedly secured to said base, and its opposite end portion provided with a pedal plate, a pulley at the upper end of said post and members carried by said post journing said pulley, a cable secured to said foot pedal extending to and over said pulley, a cable secured to said foot pedal extending to and over said pulley and terminating in a hook adapted for engagement at option in any one of said holes, said post being slotted below said pulley to permit said hook engagement and hook shift under pedal action.

JOY L. GLENN.
